UNITED STATES PATENT OFFICE.

ANTONE PERRY, OF OAKLAND, CALIFORNIA, ASSIGNOR TO SIMPLEX REBORING MACHINE COMPANY, OF OAKLAND, CALIFORNIA, A CORPORATION OF CALIFORNIA.

CYLINDER-REBORING DEVICE.

Application filed January 10, 1922. Serial No. 528,209.

To all whom it may concern:

Be it known that I, ANTONE PERRY, a citizen of the United States, residing at Oakland, in the county of Alameda and State 5 of California, have invented certain new and useful Improvements in Cylinder-Reboring Devices, of which the following is a specification.

My invention is an approved cylinder re- 10 boring device comprising means for simultaneously and uniformly adjusting the cutter bits, means for locking the bits in adjusted position, and means for centering the cutter with relation to the cylinder bore 15 without the use of a centering spider.

Referring to the drawing forming a part of this specification:

Figure 1 is a vertical section of my invention.

20 Figure 2 is a plan view of the cutter washer.

Figure 3 is a plan view of the cone bearing for the cutter stem.

25 Figure 4 is a plan view of the cutter mount.

Figure 5 is an elevation of the cutter mount.

In the drawings 1 indicates a cutter mount which is formed with a circular base 2 and 30 a cylindrical ring member 3 upstanding centrally from said base. The base 2 is provided with a plurality of radial slots 4 and 5 spaced equi-distant apart, there being four slots 5 spaced 90° apart and the inner ends 35 thereof extending under the ring member 3 nearly to the inner side of said member and below four openings 6 respectively in said member. The base 2 has also a plurality of notches 7 in its periphery spaced equi-dis- 40 tant apart between slots 4—4 and 5—5. The mount 1 is detachably secured on the end of an engine cylinder 10 by bolts 11 extending through slots 4 or 5 or through notches 7 and screwing into the screw holes 12 in 45 the end of the cylinder. The openings 6 receive the heads of the bolts 11, whereby said bolts may be screwed into holes 12 which are near the center of the cylinder. The ring member 3 has an internal thread 50 13. A bearing support 14 has an external thread 15 on its lower end, which engages the thread 13 and screws into the upper end of the ring member 3 and an external flange 16 is formed on the support 14 above the 55 thread 15, which flange engages the top of

the member 3 and limits the position to which the support 14 may be screwed into said member. The support 14 has an inverted conical bore 17 in the upper end of which is an internal thread 18. A split 60 conical bearing 19 fits in the bore 17, said bearing being provided with a plurality of radial slots 20 in its periphery extending the entire length thereof, the slot opposite the split 21 in the ring being wider than the 65 other slots to receive a pin 22 extending through the support 14, whereby the bearing is held in the bore 17 against turning. A cylindrical cutter post 23 extends through the bearing 19 and support 14. A nut 24 70 surrounds the upper enlarged end 25 of the bearing 19 and screws into the thread 18 in the upper end of the bore 17 against an annular shoulder 26 on the bearing 19 at the base of said end 25, whereby the bearing 75 19 is forced tightly into the conical bore 17 and contracted snugly around the post 23. The upper end of the post 23 is formed with a wrench grip 27. The lower end 28 of the post is conical and is threaded above said 80 conical end.

A cutter 30 includes a ring 31 and a plurality of radial bits 32 slidably mounted in radial grooves 33 in said ring. The ring 31 is internally threaded to screw on the 85 thread on the lower end of the cutter post 23. The inner ends of the bits 32 are beveled to engage the beveled lower end 28 of the cutter post 23 so that as the ring 31 is screwed on the post said beveled end 28 90 will engage the beveled inner ends of said bits and force the bits outwardly to adjust the depth of the cut of said bits. A washer 34 fits on the post 23 against the upper end of the ring 31, a key 35 being formed on 95 the inner edge of said washer which fits in the longitudinal groove 36 in the post 23 to prevent said washer from turning, which groove extends from the lower end of the post. A lock nut 37 screws on the lower 100 threaded end of the post 23 against the washer 34 and locks the cutter on the post against turning.

The cutter is rotated by a wrench applied to the wrench grip 27. The adjustment of 105 the conical split bearing 19 ensures accurate adjustment of the post 23 and the cutter 30.

Having described my invention, I claim:

1. In a cylinder reboring device, a supporting member having a vertically ar- 110

2
ranged sleeve portion and an integral flange extending at right angles to the axis of said sleeve portion, said flange having radially arranged slots of different lengths and notches in its periphery for the reception of bolts adapted to secure said supporting member to a cylinder block, the longer slots being closed at both their inner and outer ends and extending inwardly toward the axis of said sleeve portion to points which lie within the periphery of said sleeve portion, said sleeve portion having vertically arranged slots communicating with said longer slots so that the above mentioned bolts may be located partially within the confines of said sleeve portion, the integral surface of the upper end of said sleeve portion being screw threaded to receive a support for an adjustable bearing and centering member, said bearing support having a flange which is adapted to seat upon the upper end of said sleeve portion, a cutter post extending through said bearing and centered thereby, and a cutter head located upon the lower end of said cutter post.

2. In a cylinder reboring device, a supporting member adapted to be secured to a

cylinder block, said member including a part formed as a vertically extending sleeve and another part formed as a flange arranged at right angles to the said first part, radial slots in said flange, some of said slots extending to points located within the confines of said sleeve, said sleeve having vertically arranged slots to communicate with the radial slots above mentioned, a flanged bearing support screw threaded into the top of said sleeve, said bearing support having a conical seat therein, a contractible conically shaped bearing fitting within said seat and having a shoulder at its upper end, a cutter post vertically arranged within said bearing, a nut screw threaded into said bearing support and so arranged as to contact with said shoulder and to cause the conical bearing member to be contracted when the nut is screwed downwardly into said bearing support, and a cutter head upon the lower end of said cutter post.

50
In testimony whereof I affix my signature.

ANTONE PERRY.
